UNITED STATES PATENT OFFICE.

JOHN C. MCKEAN, OF WESTFIELD, MASSACHUSETTS, ASSIGNOR TO FOSTER MACHINE COMPANY, OF WESTFIELD, MASSACHUSETTS, A CORPORATION OF MASSACHUSETTS.

SELF-DRIVEN DEVICE FOR AUTOMATICALLY UNTWISTING YARN TO REMOVE THE KINKS THEREFROM.

Application filed November 11, 1925. Serial No. 68,365.

It has been practically impossible to keep yarn from kinking as it passes from the yarn supply to the warping machine. This is especially true when the warping machine 5 stops and the yarn is at rest.

The object of my invention is to provide a self-driven device arranged to exert an untwisting rolling action on the yarn as it passes therethrough to automatically untwist 10 and remove the kinks, said device in the present instance comprising a vertical support and a pair of coating plates of considerable diameters carried thereby, the lower plate being fixed to said support and 15 the upper plate being gravity operated and rotatable upon the lower plate, the yarn in its passage between the plates serving to rotate said plates at different angular speeds to exert the untwisting rolling action on the 20 yarn.

The above untwisting device is preferably used in connection with a compensating device which operates to keep the yarn comparatively taut whether the yarn is running 25 or at rest, thereby tending to keep the kinks from forming in the yarn especially when the yarn is at rest.

A practical embodiment of my invention is represented in the accompanying drawings, in which

Fig. 1 represents a detail side view of a creel with my self-driven devices for automatically untwisting the yarn included therein.

Fig. 2 represents a section taken in the plane of the line II—II of Fig. 1, looking in the direction of the arrows.

Fig. 3 represents a detail section on an enlarged scale showing a cop, the compensating device and the untwisting device.

Fig. 4 represents a detail horizontal section taken in the plane of the line IV—IV of Fig. 3, looking in the direction of the arrows.

The creel frame is denoted by 1. The cops 2 are arranged in a plurality of vertical rows, the holders 3 for the cops of each vertical row being carried by a vertically disposed supporting bar 4 pivoted in the creel frame 1 to rock on a vertical axis to swing the cops to and from their doffing position.

In proximity to each vertical supporting bar 4 I mount a vertically disposed rod 5,

around which rod the yarns are wound as 55 they pass from their cops to the warping machine (not shown herein). I have found that by winding the yarn around the bar 5 as it leaves the cop, the bar operates to keep the yarn comparatively taut whether the 60 yarn is or is not running, thereby tending to take the kinks out of the yarn when the yarn is running and also to keep the kinks from forming when the yarn is at rest.

The self-driven device for automatically 65 untwisting the kinks from the yarn by a rolling action thereon as it passes through the device comprises a vertically disposed bar 6, rotatably mounted in the creel frame 1 adjacent to the vertically disposed yarn 70 compensating rod 5, and a pair of upper and lower coating plates 7 and 8 of considerable diameters. The lower plate 8 is secured in its proper position on the bar 6 by the set screw 9 and the upper plate 7 75 rests by gravity on the lower plate 8 and is freely rotatable thereon, which upper plate may be provided with one or more weights 10, if so desired.

In operation:—When the yarn is running 80 it will rotate the upper and lower plates at different angular speeds, the upper plate being rotated at a higher angular speed than the lower plate, thus exerting an untwisting 85 rolling action on the yarn which automatically untwists the kinks therefrom.

By making the plates 7 and 8 of considerable diameters, I am enabled to obtain a very high surface speed at the periphery of the upper plate, the lower plate being rotated much slower because it is secured to the bar 6, thus exerting an extended untwisting action on the yarn and also tending to throw foreign matter outwardly away from between the plates, it being understood that 90 the yarn in passing through the plates acts to wipe their coating surfaces clean and 95 keep them polished.

I am aware of the tension devices of the 100 art of somewhat similar construction to the hereindescribed kink removing device, but the washers of these tension devices of the art are universally very much smaller than the kink removing plates of the present invention. These tension devices of the art 105 are incapable of acting to untwist the kinks from the yarn and are not intended to act for this purpose. In fact these tension de-

vices tend to bite the yarn and to run the twist back and form kinks therein. In practice I have found that by making the plates of my kink removing device about 5 four inches in diameter as compared to the one and one-half inch diameter of the washers of the tension devices of the art. I am enabled to obtain extended contact with the yarn and an untwisting rolling action 10 thereon sufficient to remove the kinks therefrom.

What I claim is:—

1. A yarn supply cop and a device driven by the yarn as it passes therethrough, said 15 device comprising a pair of coacting rotatable plates having an extended contact with the yarn and operable to remove the kinks therefrom by an extended untwisting rolling action thereon, said plates having diameters 20 greater than one-half the length of the cop from which the yarn is being drawn.
2. A yarn supply cop and a device driven by the yarn as it passes therethrough, said 25 device comprising a pair of coacting rotatable plates having an extended contact with the yarn and operable to remove the kinks therefrom by an extended untwisting rolling action thereon, said plates having diameters 30 greater than one-half the length of the cop from which the yarn is being drawn, and a 35 yarn compensating device engaging the yarn as it passes from the yarn supply to the kink removing device, operating to keep the yarn comparatively taut when the yarn is running and at rest.
3. A yarn supply cop and a device driven by the yarn as it passes therethrough, said 40 device comprising a rotatable mounted vertical support and a pair of coacting rotatable plates carried thereby having an extended contact with the yarn and operable to remove the kinks therefrom by an extended 45 untwisting rolling action thereon, said plates having diameters greater than one-half the length of the cop from which the yarn is being drawn, the lower plate being fixed to 50 said support and the upper plate being gravity operated.
4. A yarn supply cop and a device driven 55 by the yarn as it passes therethrough, said device comprising a rotatably mounted vertical support and a pair of coacting rotatable plates carried thereby having an ex-

tended contact with the yarn and operable to remove the kinks therefrom by an extended 55 untwisting rolling action thereon, said plates having diameters greater than one-half the length of the cop from which the 60 yarn is being drawn, the lower plate being fixed to said support and the upper plate being gravity operated, and a yarn compensating device engaging the yarn as it passes from the yarn supply to the kink removing device, operating to keep the yarn comparatively 65 taut when the yarn is running and at rest.

5. A plurality of yarn supply cops and a plurality of devices driven by the yarns as they pass therethrough, said devices comprising a common rotatably mounted vertical support and a plurality of pairs of coacting rotatable plates carried thereby having an extended contact with the yarn and operable to remove the kinks therefrom by an extended 70 untwisting rolling action thereon, said plates having diameters greater than one-half the length of the cops from which the 75 yarn is being drawn, the lower plate of each pair being fixed to said support and the upper plate of each pair being gravity operated.

6. A plurality of yarn supply cops and a plurality of devices driven by the yarns as they pass therethrough, said devices comprising a common rotatably mounted vertical support and a plurality of pairs of coacting rotatable plates carried thereby having an extended contact with the yarn and operable to remove the kinks therefrom by an extended 80 untwisting rolling action thereon, said plates having diameters greater than one-half the length of the cops from which the 85 yarn is being drawn, the lower plate of each pair being fixed to said support and the upper plate of each pair being gravity operated.

In testimony, that I claim the foregoing as my invention, I have signed my name this 9th day of Nov. 1925.

JOHN O. McKEAN.
